Primary Examiner — Katherine A Holbrow*Assistant Examiner* — Riya Salil Kamat(74) *Attorney, Agent, or Firm* — QUICKPATENTS, LLC; Kevin Prince(57) **CLAIM**

The ornamental design for a fitness bench mini rack system, as shown and described.

DESCRIPTION

FIG. 1 is a front perspective view of a fitness bench mini rack system, showing my new design;

FIG. 2 is a rear perspective view thereof;

FIG. 3 is a front elevational view thereof;

FIG. 4 is a rear elevational view thereof;

FIG. 5 is a right-side elevational view thereof, the left-side elevational view being a mirror image thereof;

FIG. 6 is a top plan view thereof; and,

FIG. 7 is a bottom plan view thereof.

The short dashed broken lines showing extension bars in the figures depict environmental matter and form no part of the claimed design. The long dashed broken lines show stitching and form a part of the claimed design.
